UNITED STATES PATENT OFFICE

2,441,362

APPARATUS FOR THE PRODUCTION OF
METAL INGOTS

Walter A. Kosinski, Chicago, Ill.

Application August 23, 1946, Serial No. 692,588

1 Claim. (Cl. 22—61)

1

This invention relates to the production of metal ingots. Considerable material is now lost through the production of faulty ingots. The molten mass frequently develops "pipes" or air pockets in the ingots. This results in a defective product which is totally incapable of use for many purposes. It is the principal purpose of this invention to obviate this condition.

The present invention makes entirely unnecessary the present need of capping the ingots and prevents same from adhering to the mold during manufacture. Further, the formation of sink heads will be eliminated and liquid steel blow-outs will be avoided.

More specifically the invention provides a means of imparting a constant regular vibration to the ingot mold during and after the pouring operation resulting in the creation of a plurality of more or less parallel continuous undulations in the molten mass extending from the bottom to the top surface of same and so agitating the body of the mass as to effectually prevent the formation of air pockets, voids, or the like.

The inventive idea involved is capable of receiving a variety of mechanical expressions which, for the purpose of illustrating the invention, is shown in the accompanying drawing which forms a part of this specification, and wherein—

Fig. 1 is a view in end elevation, with parts in section, of an ingot mold mounted upon a carriage under vibratory impact, and,

Fig. 2 is a top plan view of Fig. 1 taken on the line 2—2 thereof.

The reference numeral 1 denotes an ingot mold of conventional type mounted upon a carriage 2 upon track 3 extending along the pouring platform 4 arranged upon support 5 extending throughout a portion of the shop or mill.

Coextensive with one edge of platform 4 is the guard wall 6 formed or provided throughout its length with an inclined shield 7 disposed forwardly toward track 3 immediately beyond a long wall-window or opening 8 forming an awning therefor, said window and awning being preferably at an elevation approximately one-half the height of the mold.

Supported upon a runway 9 carried by braces 10 and support 5 are the rails 11 upon which the carriage 12 runs, said runway being spaced inwardly from, adjacent and parallel to, the said wall 6 and coextensive therewith, said carriage

2

having arranged thereupon the reciprocating hammer 13 with its head extending through said window for engagement with a wall of mold 1 to deliver blows thereagainst at the rate of approximately sixty per minute, said hammer being electrically, compressed air, or otherwise operated.

In operation the carriage 2 with ingot mold 1 thereon is moved along track 3 to the point of loading. At the time, and for a period thereafter, that the molten material is poured into the mold the hammer 13, having been positioned directly opposite to said mold upon runway 9, is operated directing blows against said mold setting up mold vibration that is imparted to the molten material sufficiently agitating same to effectually prevent piping or the formation therein of pockets of air. By slight movement of the carriage 12 upon rails 11 in either direction the points of application of the hammer impacts may be varied if desired. This is readily accomplished by the attendant or mechanic in charge. The operator is protected at all times from molten metal, flying sparks and the like by the guard wall 6 and shield or awning 7.

What is claimed is:

In combination with an ingot mold, a movable carriage therefor, a track for said carriage, a guard wall extending along said track, a window in said guard wall extending longitudinally thereof, a shield carried by said guard wall coextensive with said window and extending outwardly and downwardly from the upper end thereof contiguous to the path of said ingot mold and carriage, a runway adjacent said guard wall upon the side thereof remote from said carriage, rails upon said runway, a second carriage movable upon said rails, and a reciprocating hammer carried by said second carriage and extending through said window beneath said shield for engagement with the ingot mold.

WALTER A. KOSINSKI.
